DESIGN FOR A BASE, FOR A DISPLAY STAND OR THE LIKE

Maximilian C. Meyer, Brooklyn, N. Y.

Application September 19, 1940, Serial No. 95,224

Term of patent 3½ years

To all whom it may concern:

Be it known that I, Maximilian C. Meyer, a citizen of the United States, residing at Brooklyn, in the county of Kings and State of New York, have invented a new, original, and ornamental Design for a Base, for a Display Stand or the like, of which the following is a specification, reference being had to the accompanying drawing, forming a part thereof.

Figure 1 is a perspective view of a base, for a display stand or the like, showing my new design; and

I claim:

The ornamental design for a base, for a display stand or the like, as shown.

MAXIMILIAN C. MEYER.
